DOUBLE CASE PUMP

Arthur J. Nelson, San Francisco, Calif.

Application December 5, 1942; Serial No. 467,943

14 Claims.

(Cl. 103—108)

This invention relates to high pressure centrifugal pumps, and more particularly to multi-stage pumps of the type employing double casings.

High pressure centrifugal pumps usually consist of a plurality of impeller elements spaced axially on the drive shaft, and a casing structure defining working passages for the several impeller elements. In order that the casing portion defining the several volutes may be assembled about the impeller elements, it is split axially into two halves. These halves of the casing are formed of relatively complicated castings and, in addition to being split lengthwise, the castings usually are relatively thin walled so that the casing is inherently weak as regards internal pressures. An accepted practice is to enclose the casing defining the several volutes within a second outer casing, the two casings being spaced circumferentially, and to introduce into the space therebetween a fluid pressure from the pressure side of the runners or impellers. Thus a force is exerted against the outer surface of the inner casing to counteract the internal pressures of the pump.

It is difficult to effect a positive seal between the two casings at the ends of the pump for sealing the annular space therebetween against leakage of the high pressure fluid. This difficulty is amplified where pumps of this type are used for pumping oil at high temperatures and delivering it under high pressures. Due to variations in temperature between the inner and outer casings, provision must be made in the sealing arrangement for permitting relative movement of the casings. The importance of a positive seal for the annular space between the casings will be better appreciated if it be understood that the temperature of the oil being pumped may be above its flash point, and hence leakage of oil to atmosphere in the event of failure of the seal would cause it to burst immediately into flame, endangering both life and property.

It is, therefore, an object of the present invention to provide a new and improved high pressure centrifugal pump of the double casing type which is mechanically strong, safe in operation, and particularly suitable for pumping inflammable liquids at high temperatures.

Another object of the invention is to provide an improved high pressure centrifugal pump comprising an inner and an outer casing with an annular space therebetween communicating with the discharge side of the pump, and having new and novel sealing arrangements at the opposite ends of the annular space.

It is a further object of the invention to provide a new and improved sealing arrangement for the annular space between casings of a double casing, high pressure centrifugal pump whereby direct leakage of high pressure fluid from such space to atmosphere is precluded.

A further object of the invention is to provide a new and improved arrangement for mounting the inner casing of a high pressure centrifugal pump within a surrounding outer casing which includes means for permitting relative movement of the casings and at the same time precludes leakage of high pressure fluid from the space between the casings to atmosphere.

Another object of the invention is to provide a new and improved high pressure centrifugal pump of the double casing type and having a space between casings communicating with the pump discharge, the casings being so designed as to require a minimum of machining operations and yet which may be fitted together into a compact assembly of extremely high mechanical strength and in a fluid-tight relation.

Another object of the present invention is to provide a new and improved impeller assembly and a surrounding casing therefor which minimizes leakage of high pressure fluid between adjacent pump stages and which arrangement is of a greatly simplified construction.

In accordance with one form of the invention, the pump consists essentially of an impeller unit, an inner casing defining the working passages for the impellers, and an outer casing. The outer casing is of a relatively rugged cylindrical design, having an open end into which may be inserted the inner casing enclosing the impeller unit. The inner casing is rigidly secured to a heavy cover plate for the open end of the outer casing, while the opposite end of the inner casing is provided with an axial cylindrical extension adapted to be received within a cylindrical opening provided in the corresponding end wall of the outer casing. A fluid inlet passage is defined by openings provided through the casings adjacent the open end of the casing, and a fluid outlet passage is defined by a second set of openings through the casings at a point adjacent the discharge stage. An annular space between the casings is in communication with the discharge passage so that the exterior of the inner casing is subject to substantially discharge pressure to counteract the outward forces of the internal pressure. The annular space between the casings is sealed at a point between the fluid inlet and outlet passages and adjacent the open end of the outer casing.

by sealing means arranged between annular shoulders provided in the adjacent walls of the two casings. The annular space is closed at the opposite end of the casings by sealing means provided between the outer casing and the outer surface of the cylindrical extension of the inner casing, the arrangement of the cylindrical extension within the end wall of the outer casing and the sealing means being such as to permit relative longitudinal movements of the casings. The sealing means at opposite ends of the annular space is so arranged that in the event of leakage of high pressure fluid past the sealing means at either end of the annular space, such leakage will occur into low pressure fluid chambers and be recirculated within the pump.

Further objects and advantages of the invention will become apparent from a perusal of the following description, taken in connection with the accompanying drawings, while the features of novelty characterizing the invention will be pointed out with greater particularity in the appended claims.

In the drawings, Figure 1 is a longitudinal sectional view through a pump constructed in accordance with one form of the invention; Figure 2 is a radial cross sectional view through the pump, taken along the line 2-2 of Figure 1; Figure 3 is a radial cross sectional view, taken through the pump along the line 3-3 of Figure 1; Figure 4 is an enlarged longitudinal sectional view of an intermediate portion of the pump rotated through an angle of 90 degrees with respect to the plane of the sectional view of Figure 1; Figures 5 and 6 are enlarged fragmentary views of details of the pump structure shown in Figure 1.

The pump as shown consists essentially of an impeller unit comprising a shaft 10 having a plurality of axially spaced centrifugal impeller elements arranged thereon, an inner casing 11 defining working passages for the impeller unit, and an outer casing 12 enclosing the whole but spaced circumferentially from the inner casing. The pump in this instance employs ten stages, but it will become obvious as the description proceeds that the features of the invention are independent of the exact number of stages employed which may be greater or less than the number shown.

The various impeller stages are indicated by the reference characters 14 to 23, inclusive, in the order of their relative positions in the fluid circuit through the pump. As illustrated more clearly in the enlarged view of Figure 4, the impeller elements are each comprised of a disc portion 26 and a hub portion 27 keyed to the shaft 10. A snap ring 28 is provided in an annular groove about the shaft and extends into an annular groove provided in the hub portion 27 adjacent the inlet or suction edge of the element for the purpose of preventing movement of the impeller element longitudinally of the shaft in the direction of the fluid approach due to the resultant force acting against the rear side of the disc tending to move the element in such direction.

Fluid is supplied to the initial stage 14 of the pump through an inlet passage defined by openings 29 and 30 provided through the casings adjacent the open end of the outer casing 12 as viewed in Figure 1. The fluid discharged from the impeller of the first stage 14 is conducted through a pair of diametrically opposed passages 31 and 32, more clearly shown in the cross sec-

tional views of Figures 2 and 3, extending lengthwise through the inner casing to the second impeller stage 15 at the opposite end of the pump. By thus arranging the two low pressure stages at opposite ends of the pump, the stuffing box 41 at the suction end of the pump is subjected only to suction pressure, and the stuffing box 59 at the opposite end of the pump is subjected only to suction pressure plus one stage pressure. From stage 15 fluid flows successively through the adjacent stages 16, 17, 18 and 19, from which last stage the fluid flows through a second pair of diametrically opposed passages 33 and 34 through the inner casing 11 to the suction chamber for the next impeller stage 20. From the stage 20 the fluid flows successively through the next adjacent stages 21, 22 and 23, the last mentioned stage being the discharge stage of the pump. This staggered arrangement is for the purpose of eliminating high pressure differentials between adjacent stages and for balancing hydraulic thrust. At the suction end of the pump a five stage differential exists between the first stage 14 and the seventh stage 20. At the center of the pump only a four-stage differential exists between the sixth stage 19 and the tenth stage 23. Elsewhere in the pump one-stage differentials appear across the suction wearing rings. This arrangement permits a material reduction in the length of the throttles. Openings 35 and 36 in the inner and outer casings adjacent the tenth stage define a fluid outlet passage, which passage is in communication with the annular space 37 between the two casings.

The inner casing, defining the working passages for the rotor assembly, is formed by a pair of matching castings which may be assembled about the rotor and secured together in any suitable manner as by bolts (not shown). It will be obvious that castings of such a complicated nature are inherently relatively weak structural elements and incapable of withstanding any great internal pressures. In order to provide sufficient mechanical strength for the structure, the space 37 is filled with fluid under discharge pressure and the two inner casing halves are forced tightly together, the pressures obtaining internally thereof being effectively neutralized by the pressure obtaining between the casings.

The outer casing 12 is of a relatively simple cylindrical design, the side wall of which is sufficiently thick to withstand the pressure developed by the pump. The outer casing is open at the suction end, through which end the inner casing assembly may be introduced. The inner casing is provided with an extension 38 defining the inlet passage 30 and bolting flange portion 39 by which the inner casing is fastened to the cover 40 for the open end of the outer casing. The shaft 10 of the impeller unit extends through the stuffing box 41 mounted within an axial opening in the cover 40. The corresponding outer end of the shaft 10 is further mounted within a bearing (not shown) suitably supported on a bracket 42 which is also attached to the cover 40. The cover 40 is secured to the outer casing 12 by means of a plurality of annularly arranged stud bolts 43, the cover being sealed in a substantially fluid tight relation to the outer casing by means of an annular gasket 44 arranged therebetween; it being understood that the entire end space between the inner casing and the cover 40 is filled with fluid under suction pressure. The cover

40 prevents rotation of the inner casing within the outer casing, eliminating the necessity of a key therebetween, and also provides means whereby the inner casing may readily be withdrawn from the outer casing, as with jack screws.

The fluid inlet passage 29, 30 is sealed from the annular space 37 between the casings by an annular gasket 47 arranged between a pair of annular shoulders 45 and 46 provided on the adjacent surfaces of the inner and outer casings, respectively. The shoulders 45 and 46 are provided on the respective casings near the open end of the outer casing on the opposite side of the inlet passage with respect thereto. Both gaskets 44 and 47 are of a compressible material, the latter being somewhat the thicker so as to insure a tight seal between shoulders 45 and 46 capable of withstanding the high fluid pressure obtaining in space 37. However, in the event of unforeseen failure of the seal between shoulders 45 and 46, leakage of high pressure fluid therepast will take place into the low pressure fluid inlet chamber from whence it will be recirculated within the pump. It will be observed that the inner casing extension 38, on which the flange portions 39 are formed, extends axially from the peripheral edge of the inner casing so that a compressive force in a straight line is imposed by the cover against the inner casing to hold the shoulders 45 and 46 tightly together. Moreover, the inner casing extension 38 bears against the cover closely adjacent the inner circumference of the outer casing so that the shortest possible distance exists between the bearing surface and the bolts 43. Thus the lever arm therebetween is short, the bending moment correspondingly reduced, and the likelihood of the seal between shoulders 45 and 46 becoming broken due to fatigue bending of the cover is minimized. This will be more readily understood when it is considered that if the cover were made to bear against the inner casing closely about the shaft, then the cover would tend to dish outwardly in time under a heavy stress to permit separation of the shoulders. By the construction shown the inlet end of the inner casing is rigidly clamped between the outer casing cover and the outer casing shoulder 46.

By virtue of the fact that the shoulder 46 of the outer casing is disposed near the open end, it is comparatively easily accessible for accurately machining the surface so as to insure a good fit with the shoulder 45 on the inner casing.

The opposite end of the inner casing is provided with a cylindrical extension 51 which is adapted to be received within an opening 52 provided in the corresponding end wall 53 of the outer casing. In order to facilitate the assembly of the pump, the inner edge of the opening is slightly chamfered as indicated at 54 to guide the cylindrical extension into the opening 52.

A sealing arrangement is provided between the inner and outer casings and is arranged within an enlarged outer end portion of the opening 52 in the outer casing end wall 53. The sealing means comprises an annular compressible member 56 of a suitable material, such as asbestos, and which is compressed into a substantially fluid tight engagement against the outer cylindrical surface of the inner casing extension 51 by means of an annular metal compression ring 57. The compression ring 57 is forced against the seal member 56 by the flange wall 58 of the stuffing box assembly 59 provided for the corre-

sponding end of the shaft 10. The stuffing box assembly 59, fastened securely to the adjacent end wall 53 of the outer casing by means of a plurality of annularly arranged stud bolts 61, is provided with an annular shoulder 60 on the inner surface of the flange which bears against the compression ring 57 through an annular gasket 62. It will be observed that a space 63 exists between the extremity of the inner casing extension 51 and the adjacent wall of the stuffing box flange 58 so that there is no obstruction to relative axial movement between the inner and outer casings at this end. The compression ring 57 bearing against the annular seal member 56 extends beyond the end of the inner casing extension 51 so that the extension does not bear against the edge of the gasket 62, which may be forced inwardly beyond the inner edge of the compression ring 57. The inner surface of the cylindrical extension 51 engages with the circumference of the stuffing box 59 over a relatively small area only and with a relatively loose fit, so that the space 63 is in substantial communication with the suction chamber 64 of the adjacent low pressure impeller stage 15. Thus, in the event of a partial failure of the annular seal member 56, permitting leakage therepast from the annular space 37 between the inner and outer casings, the high pressure fluid will flow through the space 63 and back into the suction chamber 64, the gasket 62 precluding leakage of high pressure fluid from space 63 to atmosphere.

In order to prevent the fluid being discharged from the various impeller stages from imparting a transverse thrust to the inner casing due to the tangential flow of the liquid from the volute of the working passage and thereby distorting the opposite end seals, the volutes are so designed that fluid will be discharged from each stage to the next through diametrically opposed passages. Referring more particularly to the cross sectional view of Figure 3, it will be observed that the inner casing defines a double volute for each impeller element, that is, dual tangential passages 61 and 62, through which the fluid discharged by the impeller is led from the impeller chamber at diametrically opposite points. From the volute passages 61 and 62 the fluid flows through the corresponding openings 63 and 64 provided at the ends of the respective passages 61 and 62 to the suction chamber for the next succeeding impeller stage.

For the last, or discharge stage 23, the inner casing defines a double volute as is shown more clearly in the cross sectional view of Figure 2. As in the case of the other stages, fluid emerging from the impeller disc is led from the impeller chamber at diametrically opposed points through passages 65 and 66. The discharge end 60 of the passage 65 is disposed in alignment with the discharge opening 36 of the outer casing 12, while the outer end of the passage 66 communicates with the annular space 37 between the casings. Thus a positive flow of liquid under high pressure is assured through the annular space 37 between the casings and effectively prevents coking of oil under high temperatures in such space, which might otherwise form to block off certain areas of the space and also to interfere with ready removal of the inner casing from the outer casing in the event that it should become necessary so to do in the course of maintenance operations. Another important advantage of this feature of the invention is that the

hot oil in the annular space 37 maintains a uniform temperature around the inner casing.

It will be observed that the impeller elements of the stages 14, 20, 21, 22 and 23 have their suction ends all facing in the same direction, toward the left, while the impeller elements of the remaining stages, namely 15 to 19, inclusive, all face in the opposite direction, or toward the right. Thus, only inlet fluid pressure is imposed against the cover 40 and the shaft packing of stuffing box 41, and fluid under only suction pressure plus pressure of one pump stage is imposed against the shaft packing of stuffing box 59 at the opposite end of the pump. By such an arrangement of the impeller elements on the shaft the resultant force in the axial direction of the fluid flowing through the pump creates a minimum of thrust on opposite sides of the center of the pump.

In the assembly of the impeller unit, the various discs and bushing rings cooperating with the hubs of each may be slid over the end of the shaft and keyed in position. It will be observed, however, that the impeller discs of discharge stage 23 and the adjacent stage 19 are connected together in a back to back relation. Referring more particularly to the enlarged view of Figure 4, the hub portions 71 and 72 of impellers of stages 23 and 19, respectively, are provided with cylindrical portions extending toward each other and which extensions are threaded on the outer surface. Before the impeller elements are mounted on the shaft, the two threaded hub portions thereof are secured together by means of a threaded sleeve 73. An annular collar 74 is placed over the sleeve 73 before the second impeller element is threaded into the sleeve. The collar 74 is provided with an outwardly extending annular rib 75 which is received within a cooperating annular groove provided in the wall 76 of the two casing halves. When assembled about the rotor unit the casing halves engage the collar 74 with sufficient friction to hold it stationary with respect to the rotor. A slight space 77 is left between the hub portions 71 and 72 to permit relative angular adjustment between the two impeller elements for aligning them with their respective keyways in the shaft. Since the resultant forces acting against the two impellers thus tied together is toward the right, only a single snap ring 78 need be provided at the right edge of the hub of the impeller element 19 to hold the pair of elements in the predetermined axial position. In order more effectively to prevent flow of high pressure fluid from stage 23 to stage 19, the inner surface of the collar 74 may be provided with a plurality of grooves 81 which operate in the manner of a well known labyrinth type of packing.

Having described the principles of the invention in what is considered to be an operative embodiment thereof, it is to be understood that various details shown are merely illustrative, and that the invention may be carried out by other means.

What I claim as new and desire to protect by Letters Patent is:

1. A pump comprising a multistage impeller unit, an inner casing defining the working passages for the several impellers of said impeller unit, an outer casing, a fluid inlet through said casings adjacent one end thereof, said outer casing having an opening at the suction end thereof for assembly and disassembly of the inner casing relative to the outer casing, a fluid outlet through said casings on the opposite side of said inlet with respect to said open end, annular shoulders on said outer and inner casings adjacent said

open end between said inlet and said outlet, and means for securing said inner casing relative to said outer casing and for forcing said shoulders together into a seating relation.

2. A pump comprising a multistage impeller unit, an inner casing defining the working passages for the several impellers of said impeller unit, an outer casing, a fluid inlet through said casings adjacent one end thereof, said outer casing having an opening at the suction end thereof for assembly and disassembly of the inner casing relative to the outer casing, a fluid outlet through said casings on the opposite side of said inlet with respect to said open end, an inwardly extending annular shoulder provided on the inner circumference of said outer casing between said inlet and said outlet, an annular shoulder on the outer circumference of said inner casing adapted to be seated against said first shoulder, and means for securing said inner casing relative to said outer casing and for forcing said shoulders into seating engagement.

3. A pump comprising a multistage impeller unit, an inner casing defining the working passages for the several impellers of said impeller unit, an outer casing, a fluid inlet through said casings adjacent one end thereof, said outer casing having an opening at the suction end thereof for assembly and disassembly of the inner casing relative to the outer casing, a fluid outlet through said casings on the opposite side of said inlet with respect to said open end, a removable cover for said open end of the outer casing, said cover being subjected only to suction pressure obtaining in said inlet passage, said inner casing being rigidly secured to said cover for preventing a relative rotation of said casings, said cover providing means for withdrawing said inner casing from said outer casing.

4. A pump comprising a multistage impeller unit, an inner casing defining the working passages for the several impellers of said impeller unit, an outer casing spaced circumferentially from said inner casing, aligned fluid inlets for said casings adjacent one end thereof, aligned fluid outlets for said casings communicating with said space, said outer casing having an opening at the suction end thereof for assembly and disassembly of the inner casing relative to the outer casing, annular shoulders provided on said outer and inner casings between said open end and said outlets, and means closing the open end of said outer casing and bearing against said inner casing for clamping said shoulders into seating engagement.

5. A multistage centrifugal pump comprising at least a first, a second and a discharge stage, a shaft having an impeller element arranged thereon for each of the said stages, an inner casing defining a working passage for each of said impeller elements, said first and second stages being at opposite ends of said pump, an outer casing spaced circumferentially from said inner casing and having an open end, cover means rigidly securing said inner casing to said outer casing at said open end, a shaft opening extending through the opposite end wall of said outer casing, an axial extension of said inner casing slidably arranged within said shaft opening, a shaft packing means mounted in said opening, an inlet for said pump communicating with said first stage whereby said cover means is subjected only to inlet fluid pressure, a passage in said casing for conducting fluid discharged by said first stage to said second stage whereby the shaft packing means at the opposite end of said pump is subjected only to inlet fluid

pressure plus first stage pressure, and a passage through said casing for conducting fluid from said second stage to said discharge stage.

6. A centrifugal pump comprising an outer casing having an open end, an inner casing having an impeller means arranged therewithin, cover means rigidly securing said inner casing to said outer casing at said open end, a longitudinally extending cylindrical recess in the opposite end wall of the said outer casing, an axial extension of said inner casing slidably arranged within said recess, said recess having an enlarged outer end portion defining an annular shoulder on said outer casing, sealing means disposed in said enlarged outer end portion of said recess and arranged circumferentially of said axial extension, and means comprising a part of said outer casing for compressing said sealing means for sealing the space between said inner and outer casings.

7. A centrifugal pump comprising an outer casing having an open end, an inner casing having an impeller arranged therein, cooperating inlets in said casings adjacent said open end, cooperating outlets in said casings spaced axially from said inlets on the opposite side thereof with respect to said open end, a removable cover for said open end, said cover being subjected only to the suction pressure obtaining in said inlets, means securing said inner casing to said cover, a portion of said inner casing slidably arranged within the end wall of said outer casing at the opposite end with respect to said open end for permitting relative longitudinal expansion movements therebetween.

8. A centrifugal pump comprising an outer casing having an open end, an inner casing mounted in said outer casing and spaced circumferentially therefrom, a fluid inlet passage through said casings adjacent said open end, a fluid outlet passage through said casings on the opposite side of said inlet passage with respect to said open end and communicating with said circumferential space, annular means between said casings adjacent said open end for sealing said circumferential space from said inlet passage, a cover for said open end, an axial cylindrical opening in the opposite end wall of said outer casing, an axial cylindrical portion of said inner casing extending into said opening, an outwardly facing annular shoulder on said outer casing, sealing means seated at one end against said annular shoulder and engaging with the circumferential walls of said outer and inner casings, and means forming a part of said outer casing for compressing said sealing means for sealing the corresponding end of said circumferential space.

9. A centrifugal pump comprising an outer casing having an open end, an inner casing spaced circumferentially from said outer casing, outlets through said casings and communicating with said circumferential space, means closing said open end and securing the corresponding end of said inner casing relative to said outer casing, an axial cylindrical opening in the opposite end wall of said outer casing, an axial cylindrical extension on said inner casing slidably arranged within said opening whereby the corresponding end of said inner casing is supported in said opposite end of said outer casing, sealing means arranged between said outer casing and said cylindrical extension of said inner casing for sealing the corresponding end of said circumferential space from a low pressure area in said inner casing while permitting relative movement of

said casings, and an annular compression member for maintaining a constant compression of said sealing means irrespective of the relative expansion of the two casings.

10. A centrifugal pump comprising an outer casing having an open end, an inner casing having an impeller unit arranged therein, said inner casing being circumferentially spaced from said outer casing, a cover for said open end, an end 10 of said inner casing being secured to said cover and held fixed thereby relative to said outer casing, an outlet for said pump communicating with said circumferential space, an inlet for said pump adjacent said open end, annular means arranged 15 between said casings adjacent said open end between said inlet and said outlet for sealing said circumferential space from said inlet, an axial cylindrical opening in the opposite end wall of said outer casing, an axial cylindrical portion of said inner casing extending into said opening, an annular compressible sealing member arranged 20 between said outer casing and the circumference of said cylindrical inner casing portion, an outwardly facing annular shoulder on said outer casing, and means forming a part of said outer casing for compressing said annular member between said annular shoulder and said means whereby said corresponding end of said circumferential space is sealed but permitting axial expansion movements between said corresponding casing ends.

11. A centrifugal pump comprising an outer casing having an open end, an inner casing having an impeller unit including a shaft arranged therein, said inner casing being circumferentially spaced from said outer casing, a cover for said open end, one end of said inner casing being secured to said cover and held fixed thereby relative to said outer casing, an inlet for said pump adjacent said open end, an outlet for said pump communicating with said circumferential space, annular means arranged between said casings between said inlet and said outlet for sealing said circumferential space from said inlet, an axial cylindrical opening in the opposite end wall of said outer casing, an axial cylindrical portion of said inner casing extending into said opening, an annular compressible member arranged in said opening and engaging with the circumference of 30 said inner casing portion, and additional means closing said opening about said shaft and defining a space between it and said compressible member in communication with the interior of said inner casing.

12. A centrifugal pump comprising an outer casing having an open end, an inner casing having an impeller unit including a shaft arranged therein, said inner casing being circumferentially spaced from said outer casing, a cover for said open end, an end of said inner casing being secured to said cover and held fixed thereby relative to said outer casing, an inlet for said pump adjacent said open end, a pair of diametrically opposed outlets for said inner casing communicating with said circumferential space, an outlet 35 in said outer casing communicating with said circumferential space, means arranged adjacent said open end between said casings between said inlet and said outlets for sealing said circumferential space from said inlet, an axial cylindrical opening in the opposite end wall of said outer casing, an axial cylindrical portion of said inner casing extending into said opening, an outwardly facing annular shoulder on said outer casing, an annular compressible member arranged in said open- 40

ing between said outer casing and the axial cylindrical extension of said inner casing, and means affixed to said outer casing for compressing said compressible means whereby a seal is effected for sealing the corresponding end of said circumferential space.

13. A centrifugal pump comprising a plurality of stages, an outer casing, an inner casing spaced circumferentially from said outer casing, an impeller unit arranged in said inner casing and having a plurality of axially spaced impeller elements mounted thereon, said inner casing defining working passages for each of said impeller elements, the discharge stage impeller element being disposed intermediately of said plurality of impeller elements, said discharge stage and an adjacent intermediate pressure stage impeller elements having externally threaded hub portions extending toward each other, an internally threaded sleeve cooperatively threaded upon said hub portions fixedly securing said portions together in a predetermined axial relation, a second sleeve concentrically surrounding said threaded sleeve, said casing having a partition wall extend-

ing between said discharge stage and said intermediate pressure stage, said partition wall receiving and retaining said second sleeve stationarily about said shaft.

14. A centrifugal pump comprising a plurality of stages, an outer casing, an inner casing spaced circumferentially from said outer casing, an impeller unit arranged in said inner casing and having a plurality of axially spaced impeller elements thereof, said inner casing defining working passages for said impeller elements, the discharge stage being disposed intermediately of said plurality of stages, an intermediate pressure stage adjacent said discharge stage having an impeller element with the inlet facing in the opposite direction with respect to the inlet of the discharge stage impeller element, said discharge stage and intermediate pressure stage impeller elements having externally threaded hub portions extending toward each other, an internally threaded sleeve cooperatively threaded upon said hub portions securing said portions together in a predetermined spaced axial relation.

ARTHUR J. NELSON.
